(57) **CLAIM**

The ornamental design for a cover for a garage door transmitter/receiver, as shown and described.

DESCRIPTION

FIG. 1 is a perspective view of a cover for a garage door transmitter/receiver showing my new design in use;

FIG. 2 is a top view thereof, the bottom view being a mirror image;

FIG. 3 is a side view thereof;

FIG. 4 is a back view thereof;

FIG. 5 is a front view thereof; and,

FIG. 6 is a side view, opposite the side view shown in FIG. 3.

The light beams shown in broken lines in FIG. 1 are not part of the claimed design.
